DICTATION MASK

Henry A. Sherwood, Woodbridge, Conn., assignor to The Sound Scribe Corporation, New Haven, Conn., a corporation of Connecticut

Application August 4, 1954, Serial No. 31,734

Term of patent 14 years

(Cl. D83—1)

Fig. 1

Fig. 2

Fig. 4

Fig. 5

Fig. 3

Fig. 1 is a side view in elevation of a dictation mask showing my new design;

Fig. 2 is a front view of the same;

Fig. 3 is a top plan view of the same;

Fig. 4 is a bottom view of the same; and

Fig. 5 is a cross-sectional view, taken along the line 5—5 of Fig. 2, looking in the direction of the arrows.

The broken lines showing a hand microphone in Figs. 1, 2, and 3 are for illustrative purposes only.

I claim:

The ornamental design for a dictation mask, substantially as shown and described.
